United States Patent Office

Des. 210,271
Patented Feb. 27, 1968

210,271

BOTTLE

Alfred D. Sterges, Los Angeles, Calif., assignor to The Drackett Company, Cincinnati, Ohio, a corporation of Delaware

Filed June 23, 1967, Ser. No. 7,569

Term of patent 14 years

(Cl. D9—60)

FIG.1.

FIG.2.

FIG.3.

FIG.4.

FIG.5.

FIG.6.

I claim:

The ornamental design for a bottle, as shown.
